(57) **CLAIM**

The ornamental design for an ironing organizer, as shown and described.

DESCRIPTION

FIG. 1 is a perspective view of an ironing organizer showing my new design;

FIG. 2 is a front elevational view of the ironing organizer of FIG. 1;

FIG. 3 is a left side elevational view of the ironing organizer of FIG. 1;

FIG. 4 is a right side elevational view of the ironing organizer of FIG. 1;

FIG. 5 is a top plan view of the ironing organizer of FIG. 1; and,

FIG. 6 is a bottom plan view of the ironing organizer of FIG. 1.

The rear elevational view forms no part of the claimed design.
